FACSIMILE RECEIVER

Edmund F. Priessnetz, Baldwin, N.Y., assignor to Electronic Transmission Systems, Inc., New York, N.Y.

Filed Oct. 29, 1969, Ser. No. 19,825

Term of patent 14 years

Int. Cl. D14—01

U.S. Cl. D26—14

FIG. 1

FIG. 2

FIG. 3

FIG. 4

FIG. 5

FIG. 6

FIG. 7

FIG. 1 is a top plan view of a facsimile receiver showing my new design;

FIG. 2 is a left side elevation thereof;

FIG. 3 is a front elevation thereof;

FIG. 4 is a bottom plan view thereof;

FIG. 5 is a right side elevation thereof;

FIG. 6 is a rear elevation thereof; and

FIG. 7 is a front perspective view thereof.

I claim:

The ornamental design for a facsimile receiver, substantially as shown and described.
